18 Claims. (Cl. 235—86)

1

This invention relates to an improvement in fecundity calendars and essentially consists in certain peculiarities of the construction and arrangement of masks for indicating the fecundity days appearing on a calendar band substantially as will be hereinafter more fully set forth and claimed.

First the invention is explained by means of diagrammatic Figures 1 and 2. Figs. 3-7 illustrate an embodiment by way of example of the fecundity calendar in the shape of a flat box, Fig. 3 showing a section according to line III—III of Fig. 4, Fig. 4 a section according to line IV—IV of Fig. 3, Figs. 5 and 6 a side view and a front view, respectively, of the box, and Fig. 7 a view of a circular plate arranged in the box, Figs. 8 and 9 are illustrating a modified embodiment of the calendar with coils for rolling and unrolling the calendar band, Fig. 8 showing a middle section through the co-axial coils for rolling up and unrolling, and the circular guide path for the band, and Fig. 9 a cross section similar to that of Fig. 4.

Figs. 1, 2 were based upon a case by way of example assuming that the determination of the fertile and sterile days of a woman is concerned, whose menstruation has commenced on the third day of a month, supposing a menstrual cycle varying from 29 to 31 days.

The fecundity calendar shows a calendar band 1 of a transparent or of an opaque flexible material, upon which the dates are continuously registered in equal succession and which for example is arranged in a casing. Band 1 is suitably passed possibly closely underneath or above a fixed transparent window 2 for example in said casing for said band, or an opaque adjusting mark. The window has the width of a date inscription upon the band 1, i. e. of the calendar "calibration." Said adjusting window 2 is colored, so that the calendar date, being in a position covered by said window, appears in the color of said adjusting window.

Parallel to the band 1 two similar figure scales 3, 4 are for example on said casing fixedly arranged, starting according to Fig. 1 at the adjusting window 2. The individual figures of said scales 3, 4 show the number of days during which the feminine menstrual cycle may last; as an absolute minimum 20 days, and as an absolute maximum 41 days are being thereby assumed. Therefore only the days from 20 to 41 were inserted, the preceding figures up to the window 2 having been left out. By the term "feminine menstrual cycle" there is to be comprehended the

5 number of days lying between the commencing day of one menstruation and the commencing day of the menstruation directly following, whereby both said commencing days are to be also counted.

The distance of the figures of the scales 3, 4, from one another i. e. of their "calibration," is corresponding to the distance of dates of the calendar band 1. The arrangement of two figure scales 3, 4 is intended for using, if in the case concerned a varying menstrual cycle is to be considered, one figure scale for the shortest, the other figure scale for the longest menstrual cycle, whereby it is, according to the invention, completely irrelevant, which of the figure scales serves for the one, and which for the other menstrual cycle.

With window 2 both scales 3, 4, two indicating devices 5, 6, for example, rings in the above-mentioned casing, for the fecundity days slidably coact, said devices comprising the adjusting windows 11, 12 cooperating with the scales 3 or 4, and the masks 7, 8 indicating the fecundity dates on the band 1. The indicating devices 5, 6 may be moved in the longitudinal direction of the band 1, and be fixed in the adjusted position by a conventional fixing means 5a, 6a each including screws clamping the indicating devices to the band. With a varying menstrual cycle the one indicating device is used for the longest, and the other for the shortest menstrual cycle, whereby it is, according to the invention, completely irrelevant, which of both indicating devices is being used for the one, and which for the other menstrual cycle, because both devices 5 and 6 are constructed in similar manner.

The windows 11, 12 are covering, at a time, one single figure of the scales 3, or 4 only, so that in the window thus appears only one number, while the remaining part of the scales is covered by the indicating device. The masks 7, 8 are for the range of the fertile dates of one color, or otherwise surface-like marked, e. g. by hatching, the parts of the band 1 covered by said masks appearing in color, said parts being, together with said band, brought into a covered position by the adjusting procedure. The parts of the mask indicating the following dates of menstruation should suitably be of different color. The masks may be transparent or opaque, according to whether they come to lie above the band 1 or, if a transparent band is used, beneath said transparent band.

As fecundity days, 11 days are being assumed, comprising the physiologically implied period of

8 fecundity days, and further 3 days added for reasons of expediency. Said period of 8 days or another shorter period lying within said 11 days, which period may be looked upon as especially fertile, may still additionally be marked, e. g. by crossed lines, a special coloring or the like. The last day of the fecundity period is again distant 11 days from the commencing date of the menstruation directly following.

The mode of operation of the fecundity calendar according to Fig. 1 is as follows:

Band 1 is being drawn until the date of the commencing of the menstruation appears in the window 2, then the indicating device is moved, until the number of the longest or of the shortest menstrual cycle known to any woman, e. g. 29 and 31, appears in the window 11, or 12. Both commencing dates of the following menstruation are denoted by 9, 10. Their distance from the adjusting window 2 measured in days is thus to be seen in the windows 11, 12. The fecundity days are indicated in color by the masks 7, 8 of the indicating device upon the band 1, i. e. by the total part of the band covered by the overlapping masks, said part is indicated in the drawing by equal hatching.

If, on the contrary, a woman with an ever constant, to a day regular menstrual cycle is concerned, each of both indicating windows 11, 12 is adjusted to this single menstrual cycle.

The adjusting and reading procedure is thus, with the subject of the invention, very simple. A fast and faultless reading of the period is enabled by the fact that it appears for the user in color, i. e. in full optical covering of any date, the masks 7, 8 being suitably of equal color.

The construction according to Fig. 2 equals the construction according to Fig. 1, distinguishing merely in the arrangement of the similar scales 13, 14 for the menstrual cycles and of the reading windows 15, 16. While, namely, with the embodiment according to Fig. 1 the commencing date of the next following menstruation, denoted by 9, or 10, and the reading window 11, or 12, are at an equal distance with the indicating device 5, or 6, from the adjusting window 2, the date denoted by 9, or 10, is, according to Fig. 2, at a distance from the adjusting window 2 differing from the distance of the reading window 15, or 16. The scales 13, 14 are likewise displaced, accordingly. Thereby, however, no change is effected as to the principal relations of the row of figures and of the adjusting and reading devices, respectively, with regard to one another. The arrangement according to Fig. 2 is intended for completely excluding the possibility of confusions as to adjusting and to reading, which possibility could perhaps, according to Fig. 1, still be seen in the fact that in the three columns of figures namely: the series of dates on the calendar band 1 and both figure scales 3, 4 too great a number of figures of equal size is passing directly next to one another.

In Fig. 2 there is schematically illustrated a separate arrangement of said three columns of figures. With an embodiment of the invention, e. g. according to Figs. 3-7, said separation is realized in such a manner that the calendar band is guided over a central circular path, while both scales of figures are, each, arranged laterally from said path, so that the user, in consequence of the three dimensional separation of said parts, always has one single column of figures only before her eyes, confusions being thus avoided.

The manipulation of the fecundity calendar ac-

cording to Fig. 2 is similar to that according to Fig. 1.

When adjusting the date of the calendar band 1, on which the menstruation has commenced, to the adjusting window 2, and when further adjusting both windows 15, 16 to those numbers of the figure scales 13, 14 corresponding to the shortest, or longest duration of a varying menstrual cycle of the woman concerned, both terms 9, 10 must be distant from the adjusting window 2 by so many calendar days as is indicated by the numbers of the figure scales 13, 14 adjusted in both windows 15, 16.

The embodiment of the fecundity calendar illustrated in Figs. 3 to 7 is constructed according to the embodiment of Fig. 2, and shows the shape of a flat box. Said box is either circularly cylindrical, as illustrated, it may, however, also be oval-shaped or rectangular, square or of some other shape out of round. Together with a handy construction said shaping has, according to the invention, likewise the technical advantage that the calendar may be, thanks to said shaping, kept especially small in its main dimensions. The duration of the absolutely longest menstrual cycle is, as already mentioned, 41 days. These 41 days represent on the basis of the calendar band calibration according to Fig. 1 or 2 a considerable distance, because the date figures on the calendar band must still be well legible, and therefore must not be too small. In order to enable that the calendar be considerably smaller, said distance of 41 days is not stretched out in a straight line, but arranged as a circular arc along a cylindric path.

In adjusting the guide of the calendar band to the form of a circular arc also the other parts of the fecundity calendar are made in a circular form. In consequence of said centrical arrangement there is now, as opposed to the straight arrangement according to Fig. 1 or 2, an accordance of the calibrations of the individual calendar parts.

It should be possible to move the calendar band and both indicating devices for the fecundity dates with regard to one another without disturbances, any of said three parts possessing a certain strength of material. There follows that any one of them also has, with a concentric arrangement, a different radius. This effects, however, that the calibrations of the calendar band, of the figure scales and of the masks, and the dimensions of the windows must no longer be of equal length, but must, with a decreasing radius, become proportionally smaller.

The construction of the embodiment according to Figs. 3 to 7 is in the following described in detail.

The calendar band 1 is rolled up on the reel 17 having the form of a roll, and passes clockwise a length corresponding to the absolute maximum menstrual cycle starting below (viz. Fig. 3) around the circular arc-like fixed path 19, whereupon it leaves the box through the slot 20. The circular path 19 essentially extends over the range of a cycle, upon which the fecundity days may be read, as is provided for enabling the reading independent of the winding radius decreasing during the unrolling of the band from the coil. Before the band leaves the box, a spring 25 is acting brake-like thereupon. The path 19 may be designed in the manner of a reflector, shining or reflecting, in order to make the band 1 appear brighter. The part of the calendar band 1 which is, at a time, unrolled, is at the outside suitably cut off or torn off the slot 20 in such a way, that

the remaining end may still be well seized. By means of the knob 21 resting upon the axle 21a of the reel 17 the calendar band may, if desired, be again rolled back into the inside of the box. At each side of the reel 17 with the rolled up band 1 there is arranged a fixed circular plate 23, and 24, respectively. Both said plates are joined together by a distance ring 26 with the aid of the screws 27, and form the supporting structure of the box. Concentric to the reel axis 21a there are in said plates rotatably supported by means of the screwed sleeves 33, 34, and 35, 36, respectively, the outside discs 29, 30, which may be gradually turned round corresponding to the calibration of the calendar, with the use of a ball stopping arrangement. The ball stopping arrangement comprises the balls 32, lying diametrically opposite each other in an opening in each of the discs 23, 24, and engaging by the coil spring 31, provided in a bore hole of the distance ring 26, recesses 26a of the rotatable discs 29, 30, said recesses being arranged upon a circular line at a distance from one another. Corresponding to the variations of the cycle from 20 to 41 at least 22 recesses are provided. By the use of a coil spring 31 for two balls lying opposite each other an equal pressure is exerted upon said balls, so that the effort required for the rotation of both discs is likewise equal. The outside circumference of the distance ring 26 forms the said path 19 for the band 1. A spring 22 presses the reel 17 for the band 1 against the fixed circular plate 23, in order to attain the friction required for braking the reel. Both figure scales 13, 14 are arranged as a circular arc (Fig. 7) outside both fixed circular plates 23, 24 as near as possible to the periphery, both windows 15, 16 for said scales being situated in both rotatable circular discs 29, 30 (Fig. 5). The rotatable circular discs 29, 30 are performing, with this arrangement, the function of the indicating devices 5, 6 according to Figs. 1, 2.

The rotatable circular discs 29, 30 adjustable by hand have near their outside circumference transparent walls projecting vertically, circularly bent, and arranged concentrically to the path 19, said walls forming the masks 7, 8, for the dates of the directly following commencement of menstruation; they are in the corresponding places provided with different transparent colors, but are otherwise colorless transparent. For facilitating the manipulation during the practical use the numbers of both scales 13, 14 are suitably likewise colored, preferably differently, the windows 15, 16 may also be colored. Instead of the figures the base may likewise be provided in color, or both, the figures as well as the base. The masks may be opaque behind their part corresponding to the longest possible menstrual cycle, or the rotatable discs 29, 30 be provided with a shield (not shown) covering said part.

The lateral faces of the box formed by the outside discs 29, 30 are along their circumference engaged by a ring 37 for closing the box, said ring being at least for the length of the supporting path 19 of the calendar band 1 transparent, and provided with a window 2 before the slot 20. In Figs. 3, 4 said ring is illustrated as an independent body, it may, however, also form a part of the fixed discs 23, or 24. The ring 37 is supported with the reinforced part 37a upon the distance ring 26 of the circular plates 23, 24, and is secured against rotation by projections 40 of the plates 23, or 24. Said ring furthermore engages grooves 29a, 30a of both rotatable circular discs

29, 30. In the ring 37 there may also be provided a closable opening 137, so that the inside of the box may be accessible. This opening is shut by the transparent displaceable cover 237.

5 The manipulation of the fecundity calendar according to Figs. 3 to 7 is as follows:

The band 1 is drawn out, until in the window 2 the date of the commencement of the menstruation appears, thereupon the discs 29, 30 are turned round, until in the windows 15 or 16 the number of days of the longest, and of the shortest, respectively, or of the constant menstrual cycle appears. Through the overlapping masks 7, 8 along the circumference of the box the fecundity days may be 10 read from the band 1. For the continuous use the band is, with a constant adjustment of the menstrual cycles, to be drawn out only far enough to make the date of the commencement of the menstruation appear in the window 2.

20 According to Figs. 8 and 9 the calendar band is not drawn out of the box, but again rolled up inside the box upon a reel 42. The manipulation of both reels 17, 42 may ensue by means of the knob 21, connected to the reel 42 by means of 25 the clutch coupling 43 under the pressure of the spring 44. If the knob is pressed against the action of the spring, the connection of the coupling is released, and the coupling 45 shifted for engaging the other reel 17 for being rolled back. 30 The remaining embodiment is similar to the embodiment according to Figs. 3 to 7, the transparent ring 37 being, however, constructed curve-like, in order to magnify the figures of the calendar band situated beneath said ring.

35 Thus both windows 15, 16 may be arranged in fixed circular plates situated on the outside, and both scales of figures may be arranged upon rotatable circular discs placed inside of said plates, or instead of the windows or masks there may also 40 be used other indicating devices, as pointers or the like.

We claim:

1. Fecundity calendar, comprising a casing, a band with a date calibration rolled up in said casing, a window on the casing for indicating the date of the commencing of the menstruation appearing on said calendar band, two similar masks for indicating the fecundity days appearing on said calendar band, said masks being movable in the same direction as said calendar band, and being provided, each, with a part limiting on both sides the range of fecundity, said masks overlapping each other, and both said parts indicating by their total surface the fecundity days. 45 50 55 60

two similar fixed scales with the days of the cycle from the shortest up to the longest period between two menstruations succeeding each other, and two displaceable means, being in fixed relation to said indicating devices for the fecundity days and adapted to co-act with one of said scales, each, for adjusting the days of the cycle for the shortest, and for the longest menstrual cycle, respectively.

2. Fecundity calendar, comprising a casing, a band with a date calibration rolled up in said casing, a window on the casing for indicating the date of the commencing of the menstruation appearing on said calendar band, two similar masks for indicating the fecundity days appearing 65 70 75 80 85 90 95

similar fixed scales with the days of the cycle from the shortest up to the longest period between two menstruations succeeding each other, said scales being arranged in the same direction as the said masks, and two displaceable reading windows, being in fixed relation to said masks and adapted to co-act with one of said scales, each, for adjusting the days of the cycle for the shortest, and for the longest menstrual cycle, respectively.

3. Fecundity calendar according to claim 2, characterized in that within said parts of the masks indicating the range of fecundity one range comprising the specially fertile days is made prominent in a distinguishing manner from the remaining range of said parts.

4. Fecundity calendar, comprising a casing, a reel rotatably supported in said casing, a band with a date calibration rolled up along the circumference of said reel, a window in said casing for indicating the day of the commencing of the menstruation appearing upon said calendar band, two similar masks for indicating the fecundity days appearing upon said calendar band, said masks being movable in the form of a circular arc concentric to said calendar and overlapping each other, two similar scales with the dates of the cycle, each, from the shortest up to the longest period between two menstruations succeeding each other, said scales being fixedly arranged in the form of a circular arc for example on said casing concentrically to the said masks, two reading windows, one of which being, at a time, in fixed relation to one of said masks, and adapted to co-act with one of said scales, for adjusting the dates of the cycle for the shortest, and for the longest menstrual cycle, respectively.

5. Fecundity calendar according to claim 4, characterized in that a fixed circular path is provided as a base for the calendar band within the range of the cycle, in which the fecundity days may be read.

6. Fecundity calendar as claimed in claim 4, characterized in that said reading windows for the scales are provided on different sides of said casing.

7. Fecundity calendar as claimed in claim 4, characterized in that the masks are opaque behind their part corresponding to the longest possible menstrual cycle.

8. Fecundity calendar, comprising a flat, essentially round casing, an axle, a reel rotatably supported in said casing upon said axle, a knob resting upon said axle for actuating said reel, a band with a date calibration rolled up along the circumference of said reel, two fixed discs, one on each side of said reel, two scales with the dates of the cycle from the shortest up to the longest period between two menstruations succeeding each other, one of said scales being fixedly arranged upon each of both said circular discs in the form of a circular arc, concentrically to the said axle of said reel, a pair of circular rotatable discs, each, forming one wall of the casing, said discs being arranged laterally from said fixed circular discs, and being provided with a window, each, and a pair of masks for indicating the fecundity days appearing upon said calendar band, each of said masks being connected in the form of a circular arc, concentric to said calendar band, and to each of said rotatable circular discs, for co-acting with one of said scales for adjusting the dates of the cycle for the shortest, and for the longest menstrual cycle, respectively.

9. Fecundity calendar, comprising a flat, es-

sentially round casing, an axle, a reel rotatably supported in said casing upon said axle, a knob resting upon said axle for actuating said reel, a band with a date calibration rolled up along the circumference of said reel, two fixed circular discs, one on each side of said reel, a pair of scales with the dates of the cycle from the shortest up to the longest period between two menstruations succeeding each other, one of said scales being fixedly arranged upon each of both said circular discs in the form of a circular arc, concentrically to the said axle of said reel, a circular pair of rotatable discs, each, forming the wall of the casing, each of said discs being arranged laterally from said fixed circular discs and being provided with a window, and a pair of masks for indicating the fecundity days appearing upon said calendar band, each of said masks being connected in the form of a circular arc, concentrically with said calendar band, and to one of said rotatable circular discs, for co-acting with one of said scales for adjusting the dates of the cycle for the shortest and for the longest menstrual cycle, respectively, as well as a ring surrounding the circumference of said casing, said ring being at least partly transparent, so that the fecundity dates indicated by said mask may be seen through said transparent ring.

10. Fecundity calendar as claimed in claim 9, characterized in that said ring is connected to said fixed circular discs.

11. Fecundity calendar as claimed in claim 9, characterized in that said transparent ring is curved in its cross section in order to act as magnifying lens for the figures of the calendar band.

12. Fecundity calendar, comprising a flat, essentially round casing, an axle, a reel rotatably supported in said casing upon said axle, a knob resting upon said axle for actuating said reel, a band with a date calibration rolled up along the circumference of said reel, two fixed circular discs one on each side of said reel, scales with the dates of the cycle from the shortest up to the longest period between two menstruations succeeding each other, one of said scales being fixedly arranged upon each of both said circular discs in the form of a circular arc, concentric to the said axle of said reel, a pair of circular rotatable discs each forming a wall of the casing, said discs being arranged laterally of said fixed circular discs and being each provided with a window, and a pair of masks for indicating the fecundity days appearing upon said calendar band, each of said pair of masks being connected in the form of a circular arc, concentric to said calendar band, and to one of said rotatable circular discs, for coacting with one of said scales for adjusting the dates of the cycle for the shortest and for the longest menstrual cycle, respectively, as well as a ring surrounding the circumference of said casing, said ring being at least partly transparent so that the fecundity dates indicated by said masks may be seen through said transparent ring, and furthermore fixing means between said rotatable and said fixed circular discs, for securing the gradual turning of the rotatable discs from one of the days of the cycle to the following one.

13. Fecundity calendar as claimed in claim 12, characterized in that both fixed circular discs are connected to one another, said fixing arrangement comprising balls resiliently supporting upon the circular discs, and recesses in said

rotatable circular discs in which said balls are engaging.

14. Fecundity calendar as claimed in claim 12, characterized in that both fixed circular discs are connected to one another, said fixing arrangement comprising balls resiliently supporting upon said circular discs, and recesses in said rotatable circular discs, in which said balls are engaging, two balls, each, resting opposite each other in both said circular discs, and one coil spring, each, being provided between both balls, said coil springs acting with their ends upon said balls.

15. Fecundity calendar comprising a flat substantially round casing, an axle, a reel rotatably supported in said casing upon said axle, a knob on said axle for actuating said reel, a calendar band with a date calibration wound up on said reel, two fixed discs one on each side of said reel, scales with the dates of the cycle from the shortest up to the longest period between two succeeding menstruations, each scale being fixed upon one of said circular discs in the form of a circular arc concentric to the reel axle, a pair of circular rotatable discs each forming one wall of the casing laterally of said fixed discs and each provided with a window, a pair of masks for indicating the fecundity days on said band, each mask being connected in the form of a circular arc concentric to said band and to one of said rotatable discs for coacting with one scale, and a spring pressing said reel against a fixed disc, and another spring for braking the band.

16. Fecundity calendar comprising a casing, a reel rotatable in said casing, a calendar band with a date calibration wound on said reel, a window in said casing for indicating the day of the commencement of the menstruation appearing on the band, two similar masks for indicating the fecundity days on the band, said masks being movable in the form of an arc concentric with said band and overlapping each other, two similar scales with the dates of the cycle each from

the shortest up to the longest period between succeeding menstruations, said scales being fixedly arranged in the form of an arc concentric to said mask, two reading windows, one being at a time in fixed relation to one of said masks and coacting with a scale and another reel for winding up the band unwound from said first reel.

17. Fecundity calendar according to claim 16 and wherein the other reel is concentric with the first reel.

18. A fecundity calendar comprising a casing, a calendar band movable lengthwise in the casing and provided with a scale of ordinals representing the days of at least one month of thirty-one days window means rigid with the casing and in the path of the band and registrable with an ordinal thereon denoting the commencement of menstruation, a pair of masks each adjacent to an edge of the band and movable relatively to the casing and lengthwise of the band to positions each indicating the shortest and longest range respectively of fecundity days appearing on the band, a pair of similar fixed scales of ordinals representing at least some of the days in a menstrual cycle and each scale on the casing to one side of the band, and means each displaceable on the casing and lengthwise of a scale and in fixed relation to a mask and when registering with an ordinal of a scale denoting the end of the cycle of menstruation beginning with the ordinal in registering with the window means.
